UNITED STATES PATENT OFFICE.

FRANK E. WILCOX, OF MECHANICSBURG, PENNSYLVANIA, ASSIGNOR OF ONE-HALF TO L. E. HICKOK, OF MECHANICSBURG, PENNSYLVANIA.

VEHICLE-GEAR.

SPECIFICATION forming part of Letters Patent No. 709,068, dated September 16, 1902.

Application filed March 15, 1902. Serial No. 98,389. (No model.)

To all whom it may concern:

Be it known that I, FRANK E. WILCOX, a citizen of the United States, residing at Mechanicsburg, in the county of Cumberland and State of Pennsylvania, have invented new and useful Improvements in Vehicle-Gears, of which the following is a specification.

My invention relates to vehicle-gears, and especially to the reach and head-block plate thereof and certain parts of the gear connected therewith, the object being, first, the simplification of the same, whereby manufacture is facilitated and cheapened and provision made for quick and easy repairs by the removal and substitution of a part, and, second, the general improvement of the gear, so that it will present a neat and pleasing appearance supplemental to the characteristic advantages secured by the novel features of construction.

My invention consists in certain novelties of construction and combinations of parts hereinafter set forth and claimed.

The accompanying drawings illustrate two examples of the physical embodiment of the invention constructed according to the best modes I have so far devised for the practical application of the principle.

Figure 1 is a plan view of a double reach-iron and a head-block plate, the said plate being shown in the position it occupies when the parts of the gear are assembled. Fig. 2 is a side view of Fig. 1 in elevation, also showing the three-pronged clip, the head-block, and leaves of a spring in section and in dotted lines a three-prong king-bolt clip. Fig. 3 shows the end of the double reach-iron with the head-block plate removed. Fig. 4 is a bottom plan view of the double reach-iron. Fig. 5 is a bottom plan view of the head-block plate. Fig. 6 illustrates in full lines a single reach-iron and in dotted lines a head-block plate.

Referring to the several figures, the letter A designates the heads of the double and single reach-irons; B, the two arms of the double reach-iron; C, a concave recess formed in the head of the reach-iron; D, a hole for the reception of a king-bolt; E, holes for the rear prongs of the clip; F, a perforated lug which receives the front prong of the

clip; G, a recess to receive the cylindrical end of the lug on the king-bolt clip; H, the head-block plate; I, a recess in the head-block plate having a convex surface; J, the head-block; K, the lower leaves of a spring; L, the three-prong clip; M, the front prong; N, one of the rear prongs; O, the king-bolt clip; P, the perforated lug of the king-bolt clip; Q, the cylindrical bearing end of the clip; R, the king-bolt, and S a single reach-iron.

The method of assembling and combining the parts will be obvious upon an inspection of the drawings. The convex surface I of the head-block plate matches the concave recess C in the head of the reach-iron, the head-block and leaves of the spring are disposed about the head-block plate, the prongs M and N of the clip pass through the holes E and F, and the four elements are firmly held together by the nuts upon the ends of the prongs, which are located below the head of the reach-iron. The recesses in the head of the reach-iron and head-block plate cause the same to interlock, and thus prevent the movement of one relative to the other.

The second example of the embodiment of the invention is shown in Fig. 6, where a single reach-iron only is used.

From the foregoing description, taken in connection with the drawings, it will be seen that I have produced an improved reach-iron and head-block plate and combined them with other parts of the gear in such a manner as to fulfil all the conditions set forth as the end and object of my invention.

What I claim as new, and desire to secure by Letters Patent, is—

1. The combination with the end of a reach-iron having holes E, E, a perforated lug F, and a hole for a king-bolt, of a head-block plate; a head-block; a spring; and a three-pronged clip, the prongs of which pass through holes E, E and the perforated lug F; said reach-iron having adjacent its end a recess C, and said head-block plate provided with a recess I which matches the recess C, whereby the reach-iron and head-block plate interlock and are held together by the clip.

2. The combination with the perforated reach-iron, of a head-block plate; a head-block; a spring; a three-pronged clip L; the

said reach-iron having a hole D in the rear of the head-block and head-block plate; a king-bolt R and a king-bolt clip O having perforated lug P located below the reach-iron.

5 3. The combination in a vehicle-gear, of the reach-iron having the perforated lug F, holes E E, hole D and recess G; a head-block; spring; three-pronged clip L; and king-bolt clip O having lug P, and cylindrical bearing 10 Q which engages the recess G; a separate

head-block plate being interposed between the head-block and recessed end of the reach-iron.

In testimony whereof I affix my signature in presence of two witnesses.

FRANK E. WILCOX.
